F. J. BAKER.

OIL CUP.

APPLICATION FILED DEC. 27, 1919.

1,409,644.

Patented Mar. 14, 1922.

F. I. G. 2.

Inventor
F. J. Baker.

By *Franklin J.* Attorney

UNITED STATES PATENT OFFICE.

FRED J. BAKER, OF SIOUX CITY, IOWA.

OIL CUP.

1,409,644.

Specification of Letters Patent. Patented Mar. 14, 1922.

Application filed December 27, 1919. Serial No. 347,667.

To all whom it may concern:

Be it known that I, FRED J. BAKER, a citizen of the United States, residing at Sioux City, in the county of Woodbury and State 5 of Iowa, have invented certain new and useful Improvements in Oil Cups; and I do hereby declare the following to be a full, clear, and exact description of the invention, such as will enable others skilled in the art 10 to which it appertains to make and use the same.

This invention relates to new and useful improvements in oil cups and has for its primary object the provision of a wick feed that can be manually controlled or moved 15 in closed proximity to the bearing or the like which is receiving lubrication from the cup and then withdrawn or placed in the reservoir when desiring to stop the lubrication to 20 said device.

Another object of this invention is the provision of an oil cup of the above stated character, which shall be simple, durable and efficient, and which may be manufactured and sold at a comparatively low cost. 25

With these and other objects in view as will become more apparent as the description proceeds, the invention consists in certain novel features of construction, combination, and arrangement of parts as will be hereinafter more fully described and claimed. 30

For a complete understanding of my invention, reference is to be had to the following description and accompanying drawings, in which:—

Figure 1 is a side elevation of an oil cup constructed in accordance with my invention;

Figure 2 is a vertical sectional view of the same;

Figure 3 is a top plan view illustrating the means of closing the top of the reservoir.

Referring in detail to the drawing, the number 1 indicates a reservoir having formed upon its bottom a nozzle 2 adapted to have threaded connection with a bearing or other device which is to be lubricated. The reservoir 1 is provided with a cover 3 provided

50 with a filling opening 4 which is adapted to be closed by a pivoted cover 5. The nozzle 2 has formed thereon a tube 6 that extends upwardly in the reservoir and terminates in a close proximity to the top wall thereof

and said top wall is provided with an opening 8 disposed directly over said tube. A wick 9 has one end secured within the reservoir as illustrated at 10 while its other end is secured to the end of an operating rod or wire 11 and which rod or wire has a handle 12 formed upon its other end. When it is desired to supply lubrication to the bearing or light to which the cup is attached, the rod or wire is placed downwardly through the tube and nozzle bringing the end of the 55 wick attached thereto in close proximity to the bearing or device so that the same can be furnished with lubrication from the reservoir. When desiring to cut off the lubrication, the wick is withdrawn from the tube 60 and nozzle and placed within the reservoir. When desiring to cut off the lubrication, the wick is withdrawn from the tube 65 and nozzle and placed within the reservoir.

The top wall of the reservoir is provided with a pivoted cover 14 which is adapted to close the opening over the tube and has a slot 15 to receive the wire or rod. 70

While I have shown and described the preferred embodiment of my invention, it will be understood that minor changes in construction, combination, and arrangement of parts may be made without departing 75 from the spirit and scope of the invention as claimed.

Having thus described my invention, what I claim is:—

An oil cup comprising a reservoir having 80 an opening in its top wall, a nozzle on the bottom wall of the reservoir and adapted to be connected to a bearing, a tube secured to the nozzle and terminating adjacent the top of the reservoir, a wick in said reservoir and 85 having one end secured to the reservoir adjacent the bottom thereof, and a rod extending through the opening and secured to the other end of the wick and adapted to be passed through the tube and into the nozzle 90 for positioning the last named end of the wick in engagement with the bearing, said rod having its upper end bent angularly to form a handle and adapted to limit the movement of said rod into the reservoir, 95 tube and nozzle.

In testimony whereof I affix my signature in presence of two witnesses.

FRED J. BAKER.

Witnesses:

ANNA HANSEN,
EDNA ANDERSON.
